UNITED STATES PATENT OFFICE.

WILLIAM MILLS, OF ELIZABETH, NEW JERSEY.

DESIGN FOR A BATTERY ELEMENT.

SPECIFICATION forming part of Design No. 26,567, dated January 26, 1897.

Application filed November 30, 1896. Serial No. 614,012. Term of patent 14 years.

To all whom it may concern:

Be it known that I, WILLIAM MILLS, a citizen of the United States, residing at Elizabeth, in the county of Union and State of New Jersey, have invented and produced a new and original Design for Battery Elements, of which the following is a specification.

The essential features of the design consist in the configuration hereinafter described, and shown in the drawings, forming part of this specification, in which—

Figure 1 is a side view; Fig. 2, a sectional elevation, and Fig. 3 a plan view.

The element comprises the substantially circular disk-like top 1, from the under surface of which extends a trunco-conoidal boss 2, the top overlapping the boss, from which latter depends a cylinder 3 of less diameter than the top 1 and boss 2, which is hollow, as shown at 4, and which is provided with ex-

terior longitudinal projections 5, formed by the longitudinal flutings 6, the projections and flutings extending the entire length of the cylinder 3. At one side of the top 1 is a circular lug 7, lying in the same plane as the top 1 and projecting up from the top 1. Opposite the lug 7 is a lug 8, lying in the same plane of projection as the lug 7. Extending partially through the lug 7 and partially through the boss 2 is a circular aperture 9, which aperture is exterior to the cylinder 3.

Having described my invention, I claim—

The design for a battery element, substantially as herein shown and described.

Signed at the city, county, and State of New York this 28th day of November, 1896.

WILLIAM MILLS.

Witnesses:

B. S. WISE,

WILLIAM JACOBS.
